BOTTLE INSPECTING DEVICE

Lawrence T. Sachtleben, Camden, N. J., assignor
to Radio Corporation of America, a corpora-
tion of Delaware

Application August 18, 1937, Serial No. 159,643

4 Claims. (Cl. 88—14)

This invention pertains to apparatus for inspecting the contents of liquid-filled bottles and is an improvement on the construction described and claimed in my application Serial No. 133,992, filed March 31, 1937, now Patent No. 2,192,580, issued March 5, 1940.

In the said application, there was described and claimed an apparatus for inspecting the liquid contents of bottles and, more particularly, bottles having a portion of their surface fluted, wherein the bottle was rotated to bring the contents into rotation and then the bottle was stopped. An appropriate optical system focused one or more sharp lines of light adjacent the interior surface of the bottle and any extraneous matter in the contents would interrupt a portion of the sharply focused light, thereby producing appropriate response from a photocell which, in turn, passed impulses through an amplifier tuned to the frequency of rotation of the bottled contents, causing an appropriate indication or the discarding of the bottle by the apparatus.

The invention of the present application is an improvement on that of the said earlier application in that length of the optical system is decreased, the precision of the optical system is improved and the intensity of the illumination, particularly at portions of the bottle where foreign materials are most likely to occur, is increased.

These improvements are accomplished by improvements in the type and arrangement of the lenses used for focusing the light within the bottle.

An object of my invention is to provide an illuminating system of improved efficiency.

Another object of my invention is to provide means for directing a beam of light through a bottle with much greater light intensity nearer the bottom of the bottle than at other portions.

Other and incidental objects of my invention will be apparent to those skilled in the art from a reading of the following specification and an inspection of the accompanying drawing in which.

Figure 1 is an elevation of my improved optical system, and

Figure 2 is a plan view thereof, partly in section.

Referring first to Fig. 1, an exciter lamp 10 is provided having a filament 11 in the form of a single axial helix. The lamp is supported in the usual socket 12 and the electrical filament is maintained in predetermined position by hold-

ing the envelope of the lamp 10 in position by means of a spring-pressed cap 13 cooperating with the rounded upper end of the bulb. A concave spherical reflector, preferably of the back-silvered glass type, 14 is provided, which serves to increase the effective intensity of the illumination. Light from the filament 11 and the reflected image thereof produced by the mirror 14 passes through the cylindrical lens 15 and the diaphragm 16 toward the object to be illuminated. This cylindrical lens is preferably made of a crown glass having an index of refraction of 1.517 and is about $1\frac{1}{4}$ inches wide and $2\frac{1}{2}$ inches long, having radii on both faces of 1.432 inches. This lens is located with its nearer face at a distance of approximately $1\frac{1}{8}$ inches from the filament 11, which is substantially its own focal length. This lens therefore directs a beam of light substantially parallel transversely through the diaphragm 16.

The light from the filament 11 passing through the lens 15 is spread over a considerable vertical angle, but only the light showing within an angle of about 30° , i. e., about 15° above and below the horizontal axis of the apparatus, falls upon the bottle 17. An appropriate supporting member 18 is provided consisting of a piece of plane parallel glass, such as plate glass, and to the surface thereof are fastened the lenses 19 and 20. The lens 19, which is a plane cylindrical lens having its axis vertical, serves to focus the light in the belt 21 of the bottle where no flutes occur, the flutes themselves serving as lenses to focus the line of light within the bottle 20 in the portions 22 and 23.

Light focused within the bottle in the form of a narrow line, either by the flutes at 22 and 23 or by the lens 19, is interrupted by the passage of any obstructions in the rotating contents of the bottle, as above described, and correspondingly affects the photoelectric device 24, which is connected to an appropriate amplifier and which, in turn, operates an appropriate indicating or other signal responsive means.

The lens 19 and, likewise, the lens 20 have a width of $\frac{3}{4}$ of an inch and a radius of .646 inch and, like the lens 15, are made of crown glass having an index of refraction of 1.517, these lenses being located at a distance of $2\frac{1}{2}$ inches from the center of the bottle.

It will be apparent that a considerable portion of the light from the filament 11 passes through the lens 15 outside of the 30° angle within which it would fall upon the bottle 17. It is highly desirable, since particles of foreign material would

normally accumulate near the bottom of the bottle, to have considerably increased illumination at this point. I accordingly provide a pair of lenses 25 and 26, just below the portion of the beam normally striking the bottle, in order to direct the light which would otherwise miss the bottle, into the bottom portion thereof. These lenses each have a length measured horizontally of 1½ inches and a height of 1¼ inches, the radius of the curvature thereof being 2.63 inches, and the center line is spaced at a distance of 3.7 inches from the filament, as measured along their optical axes. These lenses refract the light passing through the lower portion of the lens 15 upwardly, causing it to strike the lens 20 which, in turn, converges it into the lower portion of the bottle 17. This arrangement increases the illumination in the lower portion of the bottle by at least three or four times as compared with the illumination at the upper parts of the bottle and correspondingly increases the sensitivity of the apparatus in detecting any foreign materials which might be in the lower portion of the bottle. The focal length of the lenses 25 and 26 is so chosen that an image of the filament 11 is formed within the nearer surface of the object with a vertical magnification of about two to one, the length of the axial coil filament 11 being about $\frac{3}{8}$ of an inch.

30 If it is desired to also use the light passing through the upper portion of the lens 15, a pair of appropriate concave reflectors 27 and 28 having cylindrical power with the axes of curvature perpendicular to the plane of the paper of Fig. 1 may be provided. These mirrors are preferably in view of their probable exposure to damage of the glass type silvered on their surfaces or they may be made of an appropriate noncorrosive metal. The curvature of the mirrors is so chosen that an image of the filament 11 is produced within the object 17 immediately adjacent to the nearer surface thereof and preferably enlarged vertically of the object in the same ratio as is accomplished by the lenses 25 and 26.

Having now described my invention, I claim:

1. Apparatus of the class described, comprising an incandescent lamp, a cylindrical lens for directing a beam of light from said lamp into an object to be inspected, an additional cylindrical lens means arranged transversely of said first

5 lens substantially outside of the normal path of light from said lamp to said object for directing light from outside of the direct beam passing through the first lens to the said object to predetermined portions of said object.

2. Apparatus of the class described, comprising an incandescent lamp, a cylindrical lens for directing a beam of light from said lamp into an object to be inspected, additional cylindrical lens means arranged transversely of said first lens substantially outside of the normal path of light from said lamp to said object for directing light from outside of the direct beam passing through the first lens to the said object to predetermined portions of said object, and cylindrical reflecting means for also directing additional light from outside of the direct beam to the said object to predetermined portions of said object.

20 3. Apparatus of the class described, comprising a light source, means for holding an object to be inspected in predetermined relation to said light source, a cylindrical lens adjacent said light source for directing a beam of parallel light from said source to said object, additional cylindrical lens means for focusing light from said parallel beam to a narrow line within said object, said cylindrical lens means all having their axes in the same plane, and additional cylindrical lens means substantially outside of the normal path of light from said lamp to said object having an axis perpendicular to the said plane for directing additional light passing through the first lens into predetermined portions of the said object.

35 4. Apparatus of the class described, comprising a light source, means for holding an object to be inspected in predetermined relation to said light source, a cylindrical lens adjacent said light source for directing a beam of parallel light from said source to said object, additional cylindrical lens means for focusing light from said parallel beam to a narrow line within said object, said cylindrical lens means all having their axes in the same plane, and additional cylindrical light deflecting means substantially outside of the normal path of light from said lamp to said object having axes perpendicular to the said plane for directing additional light passing through the first lens into predetermined portions of the said object.
